Primary Examiner — Khawaja Anwar

(57) **CLAIM**

The ornamental design for an ink cartridge for computer printer, as shown and described.

DESCRIPTION

1.-2. Ink cartridge for computer printer

1.1 : Front

1.2 : Back

1.3 : Top

1.4 : Bottom

1.5 : Left

1.6 : Right

1.7 : Perspective

1.8 : Perspective

2.1 : Front

2.2 : Back

2.3 : Top

2.4 : Bottom

2.5 : Left

2.6 : Right

2.7 : Perspective

2.8 : Perspective

1 Claim, 16 Drawing Sheets
